UNITED STATES PATENT OFFICE.

COLUMBUS K. LASSITER, OF RICHMOND, VIRGINIA.

MANUFACTURE OF SUPERHEATER UNITS.

1,090,551.

Specification of Letters Patent. Patented Mar. 17, 1914.

Original application filed June 5, 1913, Serial No. 771,852. Divided and this application filed December 2, 1913. Serial No. 804,197.

To all whom it may concern:

Be it known that I, COLUMBUS K. LASSITER, of Richmond, in the county of Henrico and State of Virginia, have invented a certain new and useful Improvement in the Manufacture of Superheater Units, of which improvement the following is a specification.

My invention relates to superheater units of the form ordinarily applied in locomotive boiler superheaters of the fire tube type, and its object is to provide a method of construction whereby superheater units of such character may be readily and inexpensively manufactured, and which will render available, as constituents thereof, drop forged or hydraulic pressed return bends, and to produce a superheater unit, as an article of manufacture, which shall be of greater strength, durability, and effectiveness in service, than those of the ordinary construction, by reason of having its parts solidly and securely connected together, and fully exempt from liability to leakage at their junctions.

The improvement claimed is hereinafter fully set forth.

In the accompanying drawings: Figure 1 is a view in elevation, of a superheater unit manufactured under my invention; Fig. 2, a longitudinal section, on an enlarged scale, through an end portion thereof; Fig. 3, a view, in perspective, of a return bend body; Fig. 4, a similar view of a return bend cap; Fig. 5, a view similar to Fig. 2, showing a modified form of return bend; Fig. 6, a longitudinal section through the same, on the line *a* *a* of Fig. 6; and, Fig. 7, a transverse section, on the line *b* *b* of Fig. 5.

As ordinarily constructed, superheater units of the class to which my invention relates are composed of parallel lines of seamless steel pipes and cast steel return bends, the ends of the lines of pipe being connected by tapping or threading them into the return bends. When so connected, leaks are frequently developed at the joints, after the units have been put in service, these being due to imperfectly made or deteriorated joints, or to strains exerted on the units in removing them from the boiler tubes. The cast steel return bends are also often found to be defective by reason of the presence of sand holes or other imperfections, necessi-

tating their rejection and loss. These objections, which are familiar to builders and operators of locomotives fitted with superheaters, are, under my invention, effectively eliminated.

Referring first to Figs. 1 to 4 inclusive of the drawings, for the practise of my invention, I provide a plurality of pipes, 1, of proper length and diameter, and return bends for the connection of the ends of two parallel lines of said pipes. The return bends, which are formed either by drop forging or by hydraulic pressure, are, as shown, of sectional construction, each return bend comprising a hollow body section, 2, which is continuously open at one end, in the form of a flattened ellipse, and is turned, at its opposite end, into two cylindrical open ended projections, disposed side by side, and matching with, that is to say, substantially corresponding in diameter, and in thickness of metal, with the ends of the pipes to be connected, and a dished cap or cover section, 3, the form of which, at its open end, is a flattened ellipse which corresponds with that surrounding the open end of the body section, as indicated in Figs. 3 and 4. The connection of the two lines of pipe is effected by electrically welding the ends of the cylindrical projections of a body section, 2, of a return bend, to the corresponding ends of the two lines of pipe, and thereafter similarly welding a cap section, 3, to the opposite end of the body section. By reason of the correspondence, in transverse section, and consequent "matching" of the ends of the pipes, body section, and cap, as above described, which is a novel and characteristic feature of my invention, there is no projection of metal beyond the abutting surfaces to be welded, at any of the several welds, and therefore the welding operation may be quickly and economically effected by the application of an alternating electric current and pressure, preferably that of air, acting on one of the members being welded, while the other is held stationary. This would not be practicable if metal projected beyond the surfaces to be welded. The two lines of pipe and the return bend are united by the above operation so as to form a solid, and, for practical purposes, an integral structure, which presents no joints and is thereby exempt from liability to leakage, and is not

subject to the loosening strains by which the ordinary threaded connections are deteriorated and rendered unfit for efficient service.

Figs 5 to 7 inclusive illustrate a structural modification of the return bend, which, in this case, is provided with removable plugs for affording access, if desired, to the interior of the pipe lines. The body section, 2, is of similar form to that before described, and a cap section, 3^a, is provided, which, instead of being cupped or dished, corresponds in transverse section, throughout its length, to the open end portion of the body section, and its outer end, which is plane, is provided with two openings, which are threaded, in line axially with the openings of the body section, to receive removable plugs, 5, which are cupped or hollowed interiorly, as shown, to prevent them from being burned out by the action of the high heat to which they are subjected. Squared projections, 5^a, are formed on the plugs, for the application of a wrench in screwing them into and out of position. The pipe lines, 1, body section, 2, and cap section, 3^a, are electrically welded together, as in the instance first described. By removing the plugs, a reamer may be inserted, for the purpose of truing out the end portions of the pipes.

My invention is, so far as my knowledge and information extend, differentiated from all construction proposed in the prior art, by the provision, as described and shown, of an independent cap section, which is welded to the open ended body section of the return bend after the cylindrical projections of the body section have been welded to the two pipe lines. In the latter welding operation,

when performed by the resistance electric welding process, a "flash" or inwardly projecting ring of metal is formed at the joints of the body section and pipe lines, the presence of which would ordinarily so materially obstruct the bores of the pipes as to render them unfit for service in a superheater unit. The opposite end of the body section being, as shown, either entirely open or closed by removable plugs, the flash, when so large as to be objectionable, can be readily and quickly removed by the insertion and rotation of a reamer, which clearing operation is effected before the cap is welded to the body section, and inasmuch as the inside transverse sectional area of the completed return bend is materially greater than that of the pipe lines, the reduction thereof by the flash formed at the joint of the body section and cap is inappreciable.

I claim as my invention and desire to secure by Letters Patent:

The improvement in the manufacture of superheater units which consists in forming a return bend body and a return bend cap, in separate sections having matching end surfaces, electrically welding each of the lines of pipe to a matching surface on one end of the return bend body, removing inward projections of metal at the welds by the application of a cutting tool, and thereafter electrically welding the cap section to the matching surface of the opposite end of the return bend body section.

COLUMBUS K. LASSITER.
